UNITED STATES PATENT OFFICE

2,404,263

SEPARATOR FOR BOILER BLOWOFF
PRODUCTS

Lyndon F. Wilson and Everett A. Preston, Chicago, Ill., assignors to Wilson Engineering Corporation, Chicago, Ill., a corporation of Delaware

Application December 18, 1944, Serial No. 568,663

3 Claims. (Cl. 183—83)

1

This invention pertains to separators for separating the blown off products, consisting principally of steam and water, from a steam boiler and constitutes an improvement over the separators disclosed in prior Patents Nos. 1,966,776, issued July 17, 1934, and 2,100,095, issued November 23, 1937.

In the blowing off of boilers, both stationary and locomotive, to relieve them of accumulated sludge and water contamination detrimental to efficient steaming, the blow-off products are discharged approximately at the rate of 150 gallons, or more, of fluid per minute. The first rush of water with its steam flash into the separator, meets cold surfaces and even though separated as effectively as subsequent delivery when the liquid is flowing in a smooth spiral downwardly around the enclosing walls of the separator, there is a brief period of recondensation of steam flash already separated. The consequence is that the condensate tends to carry along with the steam resulting in the discharge with the first steam flash of more or less hot water.

One of the purposes of our present invention, therefore, is to prevent this carry-over of water with the initial steam discharged from the muffler.

At the conclusion of a blow-off the sudden cessation of the delivery of blow-off products, resulting from the closing of the blow-off cock, has heretofore occasioned momentary spilling to a greater or less degree of water from the separator out through the steam discharge opening. Since this water carries solids in solution and suspension, the effect is to foul boiler jackets, cab windows and surfaces of following cars. This spilling is caused by the accumulation of circling water at the sides of the separator chamber which cannot immediately escape through the tangential discharge passage by which the separated water is delivered. The dropping, so to speak, of this circulating water as the vortex is destroyed by reduction of pressure and lost force, produces a splashing which results in the top spilling of the water along with the last of the discharged steam, as previously mentioned.

Another purpose of our invention is to overcome such spilling, which in the present disclosure is accomplished by providing an enlarged collecting chamber in which the water dropping from the side walls of the separator may be collected before ultimate delivery, thereby preventing it from splashing and spilling out with the steam.

Other objects and advantages of our invention

2

should be readily appreciated as the same becomes better understood by reference to the following description when considered in connection with the accompanying drawing.

5 Referring to the drawing,

Fig. 1 is a plan view of a separator embodying our invention;

Fig. 2 is a sectional view on the line 2—2 of Fig. 1; and

10 Fig. 3 is an elevation looking toward the left at Fig. 1.

The separator here illustrated is of cylindrical contour, adapted to be mounted upon the top of a locomotive boiler forwardly of the cab, as illustrated in the prior patents to which reference has been made or in any other convenient location to which the blow-off products of a boiler may be conducted. When used with a stationary boiler, the separator may be suitably supported outside the power house to deliver the separated steam to atmosphere and the liquid to the sewer.

Referring now to the drawing more in detail, it will be observed that the separator consists of a cylindrical casing 4 closed at its bottom by a wall 5 preferably upwardly curved. The top of the separator includes a dome 6 provided with a centrally located opening 7 surrounded by a depending flange 8. Secured to the under side of the dome is a depending arcuate flange 9 carrying a disc 11 disposed substantially parallel with and spaced from the lower edge of the flange 8. The disc carrying flange 9 is substantially semi-circular in contour, so that it, together with the disc 11, provides a baffle which obstructs the escape of fluid through the opening 7 and thereby contributes to the separation of the steam and water and tends to prevent the escape of water through the steam outlet 7.

Upon the dome 6 is mounted a thimble which 40 consists of a cylindrical body 12 provided with an inwardly sloping top 13 having a central opening 14 aligned with but considerably smaller in size than the opening 7. A sleeve 15 depends from the opening 14 into proximity to the plane 45 of the opening 7, so that a chamber 16 is provided by the thimble, which chamber is in communication with the opening 7.

The boiler blow-off products, consisting of steam and water containing contaminants in 50 solution and in suspension, are delivered tangentially into the casing 4 by an intake connection 17 extending through the wall of the casing into the separator, as illustrated in Fig. 2, and threaded at its outer end for connection with a pipe 55 leading from the blow-off cock.

The separated liquid is conveyed from the separator to a point of disposal by a discharge pipe 18 communicating with the separating chamber through a collecting box 19, preferably rectangular in cross-section, opening tangentially into the separator chamber to receive the liquid tending to accumulate in the bottom of the chamber. The box 19 is of greater cross-sectional area than the corresponding area of the discharge pipe 18 and is, consequently, able to receive and collect a volume of water in excess of the capacity of the discharge pipe. This structure is, therefore, adapted to accommodate the final separated water of each blow-off, thereby preventing its regurgitation and spilling out through the top with the steam, as has heretofore occurred when the discharge pipe communicated directly with the separating chamber.

In the operation of our improved separator, the blow-off steam and contaminated water are discharged tangentially into the separating chamber from the pipe 17. The liquid under centrifugal force clings to the peripheral wall of the separator and under the influence of gravity spirals downwardly in the chamber into the collecting box 19 and out through the discharge pipe 18. The steam, because of the centrifugal action upon the heavier water, separates from the water and moves toward the center of the separator and upwardly, so that it passes around the baffle 11 and out through the delivery opening 14 to atmosphere. During the initial stage of each blow-off, before the metal surfaces become heated, there is some tendency for the separated steam to recondense on the cold surfaces of the structure and to carry over as water spray with the steam from the separating chamber. The thus condensed liquid particles passing outwardly through the opening 7 from the separating chamber are, as a consequence of centrifugal action, passed not into the sleeve 15, but around the sleeve into the chamber 16 where they are collected and caused to drop back into the separating chamber. In this manner initial flashing or carrying over of condensate with the initial steam discharge from the separator is prevented.

When the blow-off cock is closed, thus terminating the blow-off operation, the final blow-off products under a diminishing pressure lag as they enter the separator and tend to drop to the bottom of the separating chamber without following the separator walls as closely as the preceding water under greater pressure. This collection of the water in the bottom of the chamber has a tendency to cause spilling or splashing of some of the water upwardly and outwardly with the discharged steam. The collecting box 19, however, of larger cross-sectional area than the discharge pipe 18, collects and accommodates this final rush of water until it can be delivered by the discharge pipe. In this manner the spilling of the final delivery of a blow-off is prevented.

The size, shape, proportion and arrangement of the various parts illustrated and described may obviously be varied within considerable limits without departing from the essence of our invention as defined in the following claims.

We claim:

1. A separator for separating the products blown off from a steam boiler, comprising a cylindrical shell having a closed bottom wall and a top wall provided with a large centrally disposed steam outlet opening defined by an annular depending lip, a thimble rising from said top wall, consisting of an upright cylinder, a top therefor having a central discharge opening of smaller area than said underlying shell outlet opening and a cylindrical sleeve depending from said thimble opening into proximity to the plane of the upper edge of said outlet opening, means for delivering blown off products tangentially into said shell, and means for receiving and discharging from said shell the separated liquid products, said means including a discharge pipe leading from the lower portion of said shell and a receiving chamber communicating tangentially with the interior of the shell and with said discharge pipe, said chamber being rectangular and of greater cross-sectional area than said discharge pipe.

2. A separator for separating the products blown off from a locomotive, comprising a cylindrical upright shell having a closed bottom and a top provided with a centrally disposed steam outlet opening, a thimble extending upwardly from said top and consisting of an upright cylinder, a sloping top wall therefor having a smaller discharge opening than the aforesaid steam outlet opening and a cylindrical sleeve depending from said opening, a discharge pipe, and a receiving chamber of greater cross-sectional area than the discharge pipe disposed tangentially to the periphery of the first mentioned shell and communicating with the interior of said shell and with said discharge pipe.

3. A fluid blow-off product separator, comprising a cylindrical shell having a closed bottom and a top provided with a central opening, means for delivering blow-off products tangentially into said shell, a cylindrical casing extending upwardly from the top of said shell, a downwardly sloping wall extending inwardly from the upper end of said casing and provided with a centrally disposed opening of smaller diameter than said shell opening, a sleeve depending from said last mentioned opening into close proximity to said shell opening, a box communicating with the lower portion of said shell through a rectangular opening, and a discharge pipe of less cross-sectional area than said box connected to said box.
